UNITED STATES PATENT OFFICE.

JAMES H. NORTHROP, OF HOPEDALE, MASSACHUSETTS, ASSIGNOR TO GEO. DRAPER & SONS, OF SAME PLACE.

SELF-THREADING LOOM-SHUTTLE.

SPECIFICATION forming part of Letters Patent No. 634,830, dated October 10, 1899.

Application filed January 31, 1898. Serial No. 577,531. (No model.)

To all whom it may concern:

Be it known that I, JAMES H. NORTHROP, of Hopedale, county of Worcester, State of Massachusetts, have invented an Improvement in 5 Self-Threading Loom-Shuttles, of which the following description, in connection with the accompanying drawings, is a specification, like letters on the drawings representing like parts.

10 This invention relates to loom-shuttles, and more particularly to self-threading shuttles, wherein the filling-thread is automatically led from the filling carrier or bobbin to the delivery-eye of the shuttle by movement of the 15 latter as it is thrown across the shed.

In the threading-block for the shuttle, hereinafter to be described, I have formed the entrance to the threading passage or slot with side walls diverging toward the point of the 20 filling-carrier to facilitate the entrance of the filling-thread and its passage through the passage and I have also provided an overlapping cover which extends over a large portion of the threading passage or slot to prevent the 25 thread from coming out of it.

Figure 1 is a perspective view of a shuttle embodying my invention with a filling carrier or bobbin in position therein. Fig. 2 is a top or plan view of the delivery end of the 30 shuttle with the threading-block removed. Fig. 3 is a like view with the threading-block in position. Fig. 4 is a side elevation of the delivery end of the shuttle, and Figs. 5, 6, and 7 are detail views in side elevation and under side and rear end elevation of the threading-block detached.

The open shuttle-body A, adapted to receive a filling carrier or bobbin B, Fig. 1, and provided with a side delivery-eye e, may be 40 and is of usual construction, the fore part of the shuttle-body being cut out or recessed at a' a², Fig. 2, to receive and position the threading-block to be described. The threading-block is shown separately in Figs. 5, 6, 45 and 7 as comprising a partly-cylindrical body b, having upturned walls b' and b², the body being seated in the recess a of the shuttle and retained in place by a suitable screw s, Fig. 4. As best shown in Fig. 7, the wall b' has 50 attached to or forming part of it a scroll c, substantially in alinement with the filling-

carrier, into which the filling-thread is led from the threading passage or slot d, formed by the wall b² and the exterior of the scroll. The wall b² is farthest from the scroll c at its 55 rear end, gradually converging to the forward part of the threading-passage d, making a flaring or divergent entrance thereto, which in actual practice greatly assists the thread in being led into the said passage. An upright 60 enlargement b³ on the wall b² enters the groove a' in the shuttle-body. The forward under part of the wall, cut away at b³ for the purpose, is held in the recess a², while its upper edge inclines toward the point of the 65 shuttle-body. The wall b' is forwardly extended to form a horn f, the curved lower edge of which guides the thread from the threading-passage d to the slot or notch e' of the delivery-eye e, said horn f having a laterally-extended head or shelf f', shown in 70 Fig. 5 as bent to coincide with the slope of the top of the wall b² and overlapping it at f² across the threading-passage d in front of and above the scroll-eye, to prevent the 75 removal of the thread from the passage. At its opposite side the head or shelf of the horn extends at f³ over the entrance to the delivery-eye e, forming with the wall a³ of the shuttle-body a passage-way for the thread to the 80 eye. When the thread enters the flaring end of the passage d, it must pass beneath the overlap f² to enter fully into the passage, and thence pass into the scroll-eye c, the horn f and part f³ of the head guiding the thread to 85 the delivery-eye e.

My invention is not restricted to the precise construction and arrangement herein shown and described, as the same may be modified without departing from the spirit and 90 scope of my invention.

Having fully described my invention, what I claim, and desire to secure by Letters Patent, is—

1. In a self-threading shuttle, having a side 95 delivery-eye, a scroll-eye in line with the filling-carrier to receive the filling-thread, a thread-passage leading to said scroll-eye and provided with a flaring entrance, and a laterally-extended horn to guide the thread from 100 the leading end of the scroll to the delivery-eye, substantially as described.

2. In a self-threading shuttle, a block provided with a thread-receiving passage, having a rearwardly-divergent wall, a scroll-eye therein substantially in line with the filling-carrier, and a horn having a laterally-extended head overlapping the thread-receiving passage in front of and above the front end of the scroll-eye, substantially as described.

In testimony whereof I have signed my name to this specification in the presence of two subscribing witnesses.

JAMES H. NORTHROP.
